INVENTOR

C. F. Hausman
BY Victor J. Evans

ATTORNEY

10 stricted in its application to the particular form of engine shown and described, or even to ignition mechanism in general, but has a wide field of usefulness in connection with the electrical art and I therefore reserve the right to all applications of the invention and to all modification and departures from the particular structure shown, falling within the scope of the claims.

What I claim is:—

20 1. The combination with the oil reservoir, the contact surface within the reservoir, the insulating contact holder extending in prox-

the contact surface within the reservoir, the insulating contact holder extending in proximity to said contact surface, and the contact element mounted in said contact holder, 35 of the resilient insulating annulus extending between said contact holder and said contact surface and surrounding the portions of said contact element adjacent said contact surface.

40 In testimony whereof I affix my signature.

CLEMENT F. HAUSMAN.
